(57) **CLAIM**

The ornamental design for a table combining infinity mirror surface and curved uni-bodied legs, as shown and described.

DESCRIPTION

FIG. 1 is a perspective top front view of a table combining infinity mirror surface and curved uni-bodied legs;

FIG. 2 is a front elevation view of the table combining infinity mirror surface and curved uni-bodied legs, the rear elevation view being a mirror image thereof;

FIG. 3 is a left elevation elevation view of the table combining infinity mirror surface and curved uni-bodied legs, the right elevation view being a mirror image thereof;

FIG. 4 is a top elevation view of the table combining infinity mirror surface and curved uni-bodied legs; and,

FIG. 5 is a bottom elevation view of the table combining infinity mirror surface and curved uni-bodied legs.

The oblique line shading in FIGS. 1 and 4 illustrates the infinity mirror arrangement.
